(57) **CLAIM**

The ornamental design for a catheter package with flip cap, as shown and described.

DESCRIPTION

FIG. 1 is a perspective view of a catheter package with flip cap of the present disclosure with the cap shown in a partially open position.

FIG. 2 is a front elevational view of the catheter package of FIG. 1.

FIG. 3 is a rear elevational view of the catheter package of FIG. 1.

FIG. 4 is a right side elevational view of the catheter package of FIG. 1.

FIG. 5 is a left side elevational view of the catheter package of FIG. 1.

FIG. 6 is a top plan view of the catheter package assembly of FIG. 1.

FIG. 7 is a bottom plan view of the catheter package assembly of FIG. 1.

FIG. 8 is a perspective view of the catheter package of FIG. 1 with the cap shown in a fully closed position.

FIG. 9 is a front elevational view of the catheter package of FIG. 8.

FIG. 10 is a rear elevational view of the catheter package of FIG. 8.

FIG. 11 is a right side elevational view of the catheter package of FIG. 8.

FIG. 12 is a left side elevational view of the catheter package of FIG. 8.

FIG. 13 is a top plan view of the catheter package assembly of FIG. 8; and,

FIG. 14 is a bottom plan view of the catheter package assembly of FIG. 8.

The broken line showing of parts of the drawings is included for the purpose of illustrating use and environment and forms no part of the claimed design.

1 Claim, 6 Drawing Sheets
